UNITED STATES PATENT OFFICE.

BENJAMIN BOASBERG, OF ST. LOUIS, MISSOURI.

PETTICOAT.

1,360,362.

Specification of Letters Patent. Patented Nov. 30, 1920.

Application filed April 12, 1920. Serial No. 373,409.

To all whom it may concern:

Be it known that I, BENJAMIN BOASBERG, a citizen of the United States, residing at the city of St. Louis, State of Missouri, 5 have invented a certain new and useful Improvement in Petticoats, of which the following is a specification, reference being had to the accompanying drawing, forming a part thereof.

10 This invention relates generally to wearing apparel and, more particularly, to a certain new and useful improvement in petticoats.

Petticoats, and especially petticoats of the 15 so-called "stout" sizes, are made with a considerable fullness of material to permit ease of movement and afford comfort at the knees and about the hips. This fullness, however, in petticoats as heretofore generally made, so far as I am aware, extends throughout the length of the petticoat, causes the petticoat to be particularly bunglesome about the ankles, impedes walking, and gives an unsightly appearance to 25 the outer skirt, which today is usually made narrow and should hang in straight lines to be neat and modish.

The principal object of my present invention is to provide a petticoat whose construction permits ease and comfort at the 30 knees and about the hips of the wearer, and yet obviates the objectionable features mentioned, the petticoat being of reduced fullness and fitting neatly at the bottom or 35 lower edge of the petticoat and giving the stylish appearance to the outer skirt so much desired.

With the above and other objects in view, my present invention resides in the novel 40 features of form, construction, arrangement, and combination of parts hereinafter described and afterward pointed out in the claims.

In the accompanying drawing,

45 Figure 1 is an elevational view of a petticoat embodying my invention;

Fig. 2 is an enlarged detail fragmental sectional view of the petticoat taken approximately on the line 2—2, Fig. 1; and

50 Fig. 3 is an enlarged fragmental perspective view of the petticoat.

Referring now more in detail to the said drawing, in which like reference characters refer to like parts throughout the several 55 views, the petticoat comprises what I will

designate a body-portion 4 and a so-called flounce 5, both of which may be of any suitable, and either of the same or different, material.

The body-portion 4, which in the finished 60 petticoat has the general shape or form illustrated, is formed at its upper end with a suitable waist-band 6, which may be gathered, as at 7, upon, and associated with, if desired, an elastic tape, not shown, for 65 yieldingly accommodating within the limits of the material of the body-portion 4 waists of different measurements.

The body-portion 4 is preferably of a 70 length to extend somewhat below the knees and is constructed throughout with considerable fullness of material, so as to permit freedom of movement and ease and comfort at the hips and knees of the wearer both in walking and sitting. Without interfering with or reducing such properties of the petticoat, I yieldably or loosely contract this fullness of material between the 75 ends of the body-portion by providing the petticoat lengthwise and preferably at its 80 rear with a pair of inverted or oppositely disposed plaits 8—8 forming what is commonly known as a box-plait. These plaits 8—8 are preferably fullest at their 85 approximate vertical center and taper toward the waist-band 6, where they are sewed or otherwise fixed, as at 9—9, to the body 4, and also toward the lower or bottom edge of the body, where they are likewise sewed or otherwise fixed, as at 10—10. Thus in a 90 simple, but efficient manner, I yieldably or loosely contract the fullness of the petticoat and provide a petticoat especially designed for "stout" figures, which, instead of the curves and bunglesomeness of petticoats 95 as heretofore constructed, has the narrow, straight lines so much desired at the present time. The plaits, being so fixed and prevented from opening at the top and bottom 100 edges of the body, obviate any bulky gathers at the waist-band, considerably reduce the width of the body to present at its lower end a modish, narrow appearance, and at the same time yieldably afford the desired fullness intermediate the waist-band and 105 lower edge of the body to freely accommodate the movements of the body.

The flounce 5 may be of any suitable length to give the petticoat the desired full length. This flounce is sewed or otherwise fixed, as 110

at 11, to the lower end of the body 4 and has a width equal only to the width of the body-portion 4 so reduced and contracted by the plaits 8, whereby I not only give the 5 petticoat an attractive, stylish lower end finish, but at the same time effect a considerable saving and economy in material.

As seen especially in Fig. 3, the waist-band 6 and also the adjacent upper part of 10 the plaited body 4 is divided by a suitable placket 12, and provided at the placket with coöperating fastening-members 13 for uniting or joining the waist-band ends about the body.

15 I am aware that minor changes in the form, construction, arrangement, and combination of the several parts of the petticoat may be made and substituted for those herein shown and described without departing from 20 the nature and principle of my invention.

Having thus described my invention, what I claim and desire to secure by Letters Patent is:

1. As a new article of manufacture, a petticoat including a body, a portion of which 25 is folded upon itself and the body thereby provided with a plait extending throughout the length of the body from its upper to its lower end, the plait being permanently 30 fixed from opening at the upper and lower ends of the body and loosely contracting the width of the body intermediate its said upper and lower ends.

2. As a new article of manufacture, a petticoat including a body, portions of which 35 are oppositely folded upon themselves and the body thereby provided with a box-plait extending throughout the length of the body from its upper to its lower end, the folds 40 forming the plait being permanently fixed from opening at the upper and lower ends of the body and loosely contracting the

width of the body intermediate its said upper and lower ends.

3. As a new article of manufacture, a petticoat including a body and a flounce attached to the lower end of the body, portions of the body being folded upon themselves and the body thereby provided with a box-plait extending throughout the length of 45 the body and permanently contracting the width of the body at its upper and lower ends, the folds forming the plait being permanently fixed from opening at the upper and lower ends of the body and loosely contracting the width of the body intermediate 50 its said upper and lower ends, and the flounce having a width equal only to the permanently contracted width of the lower end of the body.

4. As a new article of manufacture, a petticoat including a body having a waist-band at its upper end, the body at and adjacent its upper end and the waist-band being divided by a placket, and a flounce attached 65 to the lower end of the body, portions of the body at opposite sides of the placket, but extending throughout the length of the body, being oppositely folded upon themselves and the body thereby provided 70 throughout its length with a box-plait permanently contracting the width of the body at its upper and lower ends, the folds forming the plait being permanently fixed from opening at the upper and lower ends of the 75 body and loosely contracting the width of the body intermediate its said upper and lower ends, and the flounce having a width equal only to the permanently contracted width of the lower end of the body.

In testimony whereof I have signed my name to this specification.

BENJAMIN BOASBERG.
